UNITED STATES PATENT OFFICE.

CHARLES M. BRENNAN, OF NEW HAVEN, CONNECTICUT.

BOTTLE DECAPPER.

Application filed March 1, 1927. Serial No. 171,786.

This invention relates to improvement in bottle decappers, and particularly to devices adapted to be secured to a wall or other support in convenient position to enter a capped bottle for the purpose of removing the cap therefrom. The object of this invention is to provide a device of simple construction in which the cap is removed from a bottle without mutilating the cap, so that it can be replaced if desired, and also to provide a decapper which will hold the cap, when removed, in convenient position to be picked up for replacement, and the invention consists in the construction as hereinafter described and particularly recited in the claim.

In the accompanying drawings:

Fig. 1 is a face view of a bottle decapper constructed in accordance with my invention;

Fig. 2 is a side view of the same;

Fig. 3 is a top view of the same;

Fig. 4 is a vertical sectional view with the neck of the bottle shown in broken lines in position for being decapped.

In carrying out my invention, I form a single casting, preferably of iron, comprising a back-plate 5 formed with screw-holes 6, by which it may be attached to a wall or other support. Projecting forward from this plate and in a plane upwardly therefrom is a semicircular frame 7, comprising a lower lip 8 and an upper flange 9, said lip and flange being arranged in parallel planes, the inner wall 10 of the frame 7 being curved corresponding to the general curve of bottle caps.

A bottle to be decapped is placed in the device, as shown in Fig. 4 of the drawings, so that the under edge of the cap rests upon the lip 8, while the flange 9 extends over the

top of the cap. By inclining the frame, as shown, it permits of the insertion of a capped bottle into the device without having the bottle come into contact with the support. The device operates in the usual manner of decapping devices, that is, after the cap is inserted, the bottle is further tilted so that the lip 8, engaging with the lower edge of the cap, holds it against movement, while the bottle is pulled away from the cap. Owing to the semicircular form of the frame, and the parallelism of the lip and cap, the cap, after the bottle has been pulled away, will remain in the frame in convenient position to be picked up, and on account of the engagement of the lip 8 and the flange 9 around substantially half the circumference of the cap, prevents the cap from being so mutilated that it cannot be replaced on the bottle if desired. These devices are readily formed from a single casting and may be finished in any desired manner and can, consequently, be produced for very low cost for manufacture, and, due to the form of the device, the bottle can be decapped by turning it either to the right or the left, or straight outward.

I claim:

A bottle decapper, comprising a base and a frame formed integral therewith and projecting forwardly and upwardly therefrom, said frame formed with a semi-circular lip and with a semicircular flange, said lip and flange being arranged in parallel planes, the wall of the frame between the flange and lip being curved substantially as described.

In testimony whereof, I have signed this specification.

CHARLES M. BRENNAN.
